PLUMBING CLEANOUT DEVICE

Aaron J. Levine, 3147 N. Cambridge Ave.,
Chicago, Ill. 60657

Filed Aug. 28, 1974, Ser. No. 501,049

Term of patent 14 years

Int. Cl. D8—05

U.S. Cl. D8—68

FIG. 1 is a rear elevation of a plumbing cleanout device embodying the design;

FIG. 2 is a side elevation of the plumbing cleanout device illustrated in FIG. 1;

FIG. 3 is a top plan view of the plumbing cleanout device illustrated in FIG. 1;

FIG. 4 is a bottom plan view of the plumbing cleanout device illustrated at FIG. 1; and

FIG. 5 is a front elevation of such plumbing cleanout device.

I claim:

The ornamental design for a plumbing cleanout device, substantially as shown.
